UNITED STATES PATENT OFFICE.

THOMAS J. EDWARDS, OF CANTON, OHIO.

DESIGN FOR A CABINET-DESK.

47,813.

Specification for Design. Patented Sept. 14, 1915.

Application filed November 27, 1914. Serial No. 874,344. Term of patent 7 years.

To all whom it may concern:

Be it known that I, THOMAS J. EDWARDS, a citizen of the United States, residing at Canton, in the county of Stark and State of Ohio, have invented a new, original, and ornamental Design for Cabinet-Desks, of which the following is a specification, reference being had to the accompanying drawing, forming part thereof.

The figure is a perspective view of a cabinet desk, showing my new design.

I claim:

The ornamental design for a cabinet desk, as shown.

THOMAS J. EDWARDS.

Witnesses:

LORIN C. WISE,
FLORENCE RIBLET.
